SAFETY LATCH AND LOCK FOR DOOR
OPERATORS

Adolf H. Schaffert and John R. Montgomery,
Youngstown, Ohio, assignors to Truscon Steel
Company, Youngstown, Ohio, a corporation of
Michigan

Application October 14, 1930. Serial No. 488,654

11 Claims. (Cl. 268—59)

The present invention while adapted for other analogous purposes, is primarily intended for large doors used in buildings and warehouses. These doors are of the lift type, ordinarily made in sections and moved vertically to their open positions. Being of relatively great weight, should the elevating means, as for example a chain or other cable break, they are apt to drop by gravity and cause serious injury.

10 The object of the present invention is to provide a novel and simple form of mechanism for catching and holding the door should the elevating means break or become inactive.

15 A further and important object is to provide safety apparatus of this character which will also constitute a lock for preventing the doors being improperly or surreptitiously opened.

In the accompanying drawings:

Figure 1 is an inside elevation of a door structure showing the elevating means and the safety mechanism.

Figure 2 is a detail sectional view through one corner of a door section on an enlarged scale and illustrating the safety latch in its inactive position.

Figure 3 is a sectional view on the line 3—3 of Figure 2.

Figure 4 is a view similar to Figure 3, but illustrating the safety latch in its locking position to hold the door closed.

Figure 5 is a sectional view on the line 5—5 of Figure 1.

Figure 6 is a view in elevation of a portion of the guideways for the door sections.

35 Figure 7 is a sectional view on the line 7—7 of Figure 6.

In the embodiment disclosed, a doorway 8 is provided with a frame including side members 9 that extend above the top of the doorway where they are connected to a cross beam structure 10. The side members 9 include sets of guideways 11 preferably formed by a backing plate 12 with outer vertical angle bars 13 and abutted central angle bars 14 suitably secured, as by welding, to the plate 12 and outstanding therefrom to provide the two guideways as shown in Figure 7. The backing wall 12 and the inner flanges of the angle bars 13 and 14 are provided at intervals with openings 15, the end walls of which form 45 stops or shoulders.

Slidably mounted in the guideways 11 are vertically movable door sections 16 and 17 which may be of any desired character. The lower section 16 is shown as panelled. The upper section 17 is provided with windows. Suitable means are provided for elevating the two sections, preferably so that the lower section will move twice as fast as the upper section and the two sections will be located side by side when the door is elevated and the doorway 8 opened. As illustrated a motor 18, controlled by any suitable means, drives a cable 19 that passes around the sheaves 20 of drums 21 located at the upper corners of the door frame. Over these drums pass cables in the form of chains 22, each fixed at one end to the cross beam 10 as shown at 23 and having its other end supporting a counterweight 24. The cables 22 are looped between their points of fastening 23 and the drum 21 and pass around sheaves 25 at the upper corners of the upper section. These sheaves 25 are journaled on arms 26 of safety latches 27 pivoted to the upper corners of the upper section 17. The lower section 16 of the door is lifted by chain cables 28 attached to the upstanding arms 29 of similar safety latches 30 pivoted to the upper corners of the lower section 16. It will be understood that these cables 28 pass over the drums 21. They are shown broken off in Figure 1 in order to avoid confusion.

As the latches 27 and 30 are similar in all respects, except for the chain connections, the detail illustration in Figures 2—4 of one of the latches for the lower door section, it is believed, will be sufficient for all. The lower door section 16 is provided with a tubular frame 31 and at the upper corner this frame is slotted in its top as shown at 32, and in its side as illustrated at 33. The latch 30 is pivoted at 34 within the frame 31 and has its upstanding arm 29 projecting through the slot 32. The other end of this latch 30 is in the form of an arm 35 having a flat bearing edge 36 on the underside of its free end and also having an upstanding locking hook 37. The cable 28 is connected to the arm 29 by a yoke 38 having an adjustable connection with said arm 29 through the medium of a bolt 39. A coiled spring 40, having a yoke connection 41 with the arm 29, extends rearwardly from said arm and is engaged with a hook 42 adjustably mounted in a bracket 43 on the frame 31. Preferably the frame on op- 100

posite sides of the slot 32 is reenforced as shown at 44.

The relation of the arms 29 and 35 of the latch 30 is such that when there is a strain on the lifting cable 28 the arm 29 will be vertical, the spring 40 will be under tension, and the locking hook and shoulder 36 will be within the slot 33, so that the hook does not interfere with the raising and lowering of the door. If, however, the cable 28 should break when the door is elevated and the arm 29 is thus relieved of the lifting strain, the spring 40 will act to swing the latch so as to carry the arm 35 outwardly and it will enter one of the openings 15 of the guideway. The flat shoulder will thereupon come to rest on the bottom wall of one of these openings, while the upper side of the arm will abut the outer reinforcement 44 as shown in dotted lines in Figure 2. The door therefore cannot drop, but will be caught and held, thereby avoiding any injury or catastrophe. In addition the operating mechanism is such that when the door is lowered to its closed position, the lifting chain 28 is allowed to slacken so that the latch will swing outwardly under the action of the spring 40 and enter one of the openings. It does not now support the door, but as shown in Figure 4 if an endeavor is made to raise the door, for example, by prying under it, the hook 37 will engage the top wall of the opening in which the end of the arm is located and prevent any material elevation of the door.

As already stated, the latches for the upper door section are constructed in precisely the same manner and operate in the same way, except that instead of a direct connection between each cable and its latch, the cable passes around the sheave 25 journaled on the arm 26.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the advantages of the invention.

What we claim, is:

1. In combination with a doorway having a frame including vertical guideways at the sides of the doorway, of a door slidable in the guideways, a stop associated with the guideways, a latch mounted on the door and adapted to engage the stop when the door is closed to lock the door against opening, a cable for elevating the door, said cable being connected to the latch and when under strain holding said latch away from the stop, and means for putting strain on the cable to elevate the door, said means permitting the cable to slacken when the door is closed and thereby allow the latch to engage the stop and lock the door against opening.

2. In combination with a doorway having a frame, and a door movable between an elevated position and a lowered closed position across the doorway, of a cable for elevating the door, and a combined safety latch for preventing the door from dropping if released from the cable and for locking the door in its lowered closed position against elevation by means other than the cable.

3. In combination with a doorway having a frame and a door movable between an elevated position and a lowered closed position across the doorway, of a cable for elevating the door, and

a combined safety latch for preventing the door from dropping if released from the cable and for locking the door in its closed position, said latch being held against its safety holding function by the cable and being released by the cable when the door is lowered to lock said door against elevation by means other than the cable.

4. In combination with a doorway including a frame, of guideways formed at the sides of the frame, vertically movable door-sections engaged in the guideways, stops formed in the guideways, latches pivoted to the upper corners of the door sections and movable into association with the stops, springs for thus moving the latches, cables connected to the door sections through the medium of the latches and when under strain holding the latches against engagement with the stops, and means for putting strain on the cables to elevate the door sections, said means giving slack to the cables when the door sections are closed to permit the latches to engage the stops and lock the door sections.

5. In combination with a door frame having a channeled guideway and openings formed in the bottom of the guideway, providing stops, of a door slidable in the channel of the guideway, a latch movably mounted on the door and movable into engagement with the stops, and a lifting cable for the door connected to the latch and when under strain holding the latch from engagement with the stops.

6. In combination with a door frame having sets of channeled side guideways and openings formed in the bottoms of the guideways, providing stops, door sections slidable in the channels of the respective sets of guideways, latches pivotally mounted on the upper corners of the door sections and having portions that swing into the openings, springs for swinging the latches to cause said entry, and lifting cables for the door sections connected to the latches and when under strain holding them against movement by the springs.

7. In combination with a door frame having a guideway and stops formed therein, of a door having a tubular frame slidable in the guideway, a latch pivoted within the tubular frame and having a portion movable beyond the same into engagement with the stops, and a lifting cable for the door connected to the latch and when under strain holding the latch from engagement with the stops.

8. In combination with a doorway including a channeled guideway having a bottom provided with openings, a door having a tubular frame portion slidably engaged in the guideway, a latch mounted in the tubular portion of the door and having a holding portion that is movable beyond the same into the openings, and an elevating cable for the door engaged with the latch and when under strain, holding it out of said openings.

9. In combination with a doorway including a channeled guideway having a bottom provided with openings, a door having a tubular frame portion slidably engaged in the guideway, a latch mounted in the tubular portion of the door and having a holding portion that is movable beyond the same into the openings, said latch also having an upstanding portion that projects out of and above the frame, and an elevating cable for the door engaged with the upstanding portion of the latch and when under strain, holding it out of said openings.

10. In combination with a doorway and a door movable between an elevated and a lowered position across the doorway, means for elevating

and lowering the door, a safety device controlled by the elevating means and operating when it fails to prevent the door dropping, and means with which the safety device engages when the door is lowered for holding the door against elevation by means other than said elevating means.

11. In combination with a doorway and a door movable between an elevated and a lowered position across the doorway, means for elevating and lowering the door, a stop and locking means

at the doorway, and a safety latch controlled by the elevating means and operating when it fails to engage the stop and prevent the door dropping said latch having a hook portion that engages the locking means for holding the door against elevation by means other than said elevating means.
